UNITED STATES PATENT OFFICE.

HENRY T. COATES, OF GERMANTOWN, PENNSYLVANIA.

REINFORCED CONCRETE STRUCTURE.

Application filed June 19, 1920. Serial No. 390,066.

This invention relates to reenforced concrete structures.

The object of the invention is to provide a reenforced concrete structure which is simple, efficient, and economical to build.

A further object is to provide a chair device for supporting the reenforcing rods employed in reenforced concrete structures, which is simple, efficient, economical to construct and to apply, and wherein the reenforced rods are maintained in proper position within the body of the concrete structure.

Other objects of the invention will appear more fully hereinafter.

The invention consists substantially in the construction, combination, location and arrangement, all as will be more fully herein-after set forth, as shown in the accompanying drawings, and finally pointed out in the appended claims.

Referring to the accompanying drawings,

Fig. 1 is a view in perspective, showing a portion of a form, a reenforcing rod and chairs for supporting the latter, in accordance with my invention, these parts being assembled ready to receive the concrete.

Fig. 2 is a view similar to Fig. 1 showing a slightly different type of reenforcing rod.

Fig. 3 is a view showing another type of reenforcing rod and the application of concrete.

Fig. 4 is a view in section on the line 4, 4, Fig. 3.

Fig. 5 is a top plan view of a reenforcing rod supporting chair embodying my invention.

Fig. 6 is a view in perspective of a slightly modified form of chair embodying the principles of my invention.

Fig. 7 is a top plan view of the same.

Fig. 8 is a view in side elevation partly broken away showing another form of chair embodying my invention.

Fig. 9 is a transverse section of the same in the line 9, 9, Fig. 8.

Fig. 10 is a view similar to Fig. 8 showing still another form of chair embodying the principles of my invention.

Fig. 11 is an end view of the form of chair shown in Fig. 10.

Fig. 12 is a broken view in perspective of

intersecting reenforcing rods and a chair for one of them.

The same part is designated by the same reference numeral wherever it occurs throughout the several views.

In the erection of reenforced concrete structures it is a common practice to build up with planking suitable forms to the required shape, such as pillars, walls, floors, and the like, and then place suitable steel reinforcements within the forms and finally to pour into or fill the forms with concrete so as to surround the reenforcing members.

In order to secure the best results the reenforcing members should be efficiently held in place within the forms and while the concrete is being poured. For this purpose wire devices or cradles have been employed, these devices being suitably nailed to the forms and the reenforcing rods being placed thereon. These wire cradles, however, have not been satisfactory for the reason that they are more or less fragile or resiliant and bend under the weight of the rods, thereby displacing the rods, and, moreover, it takes time and labor to nail them with sufficient secureness to the form, to prevent them from bending, and when they become bent or deflected, it is a difficult job requiring time and labor to reposition them or the rods which their bending has caused to become deranged.

Again, it is desirable to maintain the reenforcing members a substantially fixed distance from the outer surface of the concrete body, and in case a fragile chair or support for the reenforcing member is employed, its collapse or deformation when the weight of the reenforcing member is imposed thereon, will permit the reenforcing member to become displaced and to approach the outer surface of the concrete body, and hence if the concrete body should be subjected to heat, as when a fire occurs in a building in which such reinforced body is employed, the danger is incurred of the reenforcing member being melted by the heat, thereby destroying its reenforcing function and hence weakening the entire body.

It is among the special objects of my present invention to provide a supporting chair device for the reenforcing rods of concrete

structures which avoids the objections above noted, and others, which is simple in structure, economical to manufacture, and can be easily and readily applied in position for use, and which not only cannot bend under the weight of the reenforcing rod imposed thereon, but which materially adds to the strength of the reinforced structure, and which is capable of maintaining the re-enforcing member at the required distance from the outer surface of the concrete body.

In carrying out my invention I provide a chair upon which the reenforcing rod or bar is positioned, and which not only offsets the rod or bar from the form so as to permit the same to be completely surrounded by and imbedded in the concrete, but which holds or retains such rod or bar in place. In accordance with one embodiment of my invention I form the chairs by stamping the same out of sheet steel, and pressing or stamping them into substantially channel or V-shape in cross section, and in order to form retaining and holding seats for the reenforcing rods or bars I form notches or depressions in the outer edges of the flaring or inclined side walls of the chairs, into which the rods, which are disposed in transverse relation with respect to the chairs, are received. This arrangement provides a support for the reenforcing member at two separated points on each chair.

In the drawing the chairs are indicated, generally, by reference numeral 15. These, in the particular form shown, and as above stated, are stamped out of comparatively thin sheet steel and into substantially V-shape, the inclined flaring walls being indicated at 16, 17. The outer edges of these flaring or inclined walls are formed with notches or depressions 18 therein to form seats to receive the transversely disposed re-enforcing rods.

Referring to Figs. 1 and 2, the planking of the form is indicated at 19, and in Figs. 3 and 4, the poured concrete surrounding and imbedding the rod and chairs is indicated at 20.

In assembling the parts in the form, the rods are simply laid into the notches or seats 18 of the chairs, the latter resting upon or against the planking 19 of the form. It will be understood of course that each rod may be supported by as many of the chairs as desired.

The form of reenforcing rod or bar is not of consequence. In Fig. 1 I have shown a plain round steel bar 21. In Fig. 2 a re-enforcing cable section 22 is shown, and in Fig. 3, a grooved bar 23 is employed.

In order to facilitate the assembling of the chairs in place to receive the reenforcing bars, especially in constructing columns or vertical walls, holes, indicated at 24, see Figs. 4, 5, and 7, may be punched through

the crotch or angle portion of the V-shaped or channel chair stamping through which tacks or nails may be driven into the form boards. Where this may not be desirable, the chairs may be otherwise positioned, as, for example, by suitably tying them to the rods, by means of cord, wire, or the like, as indicated at 25, in Figs. 1 and 2. For this purpose the inclined side walls of the stampings forming the chairs may be provided with holes 26, through which the retaining wire or cord is passed.

Where the chairs rest their full length against the surface of the form boards, as indicated at 27, Fig. 4, after the concrete is poured and the form boards are removed the metal of the chairs will be exposed along the line of the exterior surface of the apex of the chair. This exposed metal surface while not objectionable in many cases, and can be easily covered over by the application of a coat of paint, still, it may sometimes be desirable to avoid undue exposure of the metal of the chairs through the concrete surface. To accomplish this the extreme ends of the apex rib of the chairs may be expanded outwardly or away from the body of the chair as indicated at 28, Figs. 8 and 9. The same result can be secured in other ways. For example, tongues 29, see Figs. 10 and 11, slit from the ends of the chair bodies and bent outwardly away from such bodies. These expanded or extended portions, in the one case, or the tongues in the other case, take the bearing of the chairs, against the surface of the form boards, thereby reducing to a minimum the extent of exposure of the metal of the chairs through the surface of the concrete when the form boards are removed. In addition, the concrete is also enabled to surround the entire bodies of the chairs except for the small areas of the extensions 28 or tongues 29, thereby more effectually anchoring the chairs in the concrete and enabling them to render material aid in the reinforcement of the concrete. The V-shape or channel of the bodies likewise contribute to this increased reinforcing capacity of the chairs.

In practice I prefer to slightly bend or curve the inclined side walls, one or both, of the chairs, in the direction of the length thereof. This curvature is indicated by the dotted lines 30 in Figs. 6 and 7, and is required to be only slight. By reason thereof added strength is secured to resist the bending strain of the weight of the bar when imposed transversely across the longitudinally bent sides of the chair, while at the same time a better anchorage of the chair in the concrete is also secured.

Of course my invention is not to be limited with respect to number or relation of reenforcing rods. It is ordinary practice to employ reenforcing rods displaced in angular

lar relation to each other, the ones crossing the others, depending upon the nature and character of the structure to be built. In Fig. 12, I have shown two rods 31, 32, so disposed with relation to each other.

From the foregoing description it will be seen that I provide an exceedingly simple, strong, economical and efficient reenforcing rod chair device for use in reinforced concrete structures.

Having now set forth the objects and nature of my invention and various structures embodying the principles thereof, what I claim as new and useful and of my own invention, and desire to secure Letters Patents is:

1. A chair support for the rods or bars of reinforced concrete structures comprising a

trough sheet metal member of channel shape to form diverging solid walls, the outer edge 20 of said walls having V-shaped seats to receive and hold the reenforcing bar.

2. A chair support for the rods or bars of reinforced concrete structures comprising a metal member formed into channel 25 shape, the side walls of the chair being curved in the direction of their length.

3. A chair support for the rods or bars of reinforced concrete structures comprising a sheet metal stamping formed into substantially 30 V-shape open-ended trough, the walls of said trough being curved.

In testimony whereof I have hereunto set my hand on this 3rd day of June A. D., 1920.

HENRY T. COATES.
